CONTAINER

Swan Smith, White Bear, Minn., assignor to
David C. Shepard, St. Paul, Minn.

Application December 26, 1934, Serial No. 759,212

10 Claims. (Cl. 229—5.7)

My invention relates to containers and has for an object to provide a container and a method of forming the same, whereby a separate wall structure and a bottom may be securely and firmly attached to one another.

An object of the invention resides in constructing the wall structure and bottom from a flexible material such as paper and in forming on the bottom a flange integral with the bottom and bent downwardly therefrom, said flange being adapted to lie adjacent the lowermost marginal portion of said wall structure.

Another object of the invention resides in providing a metal hoop, U-shaped in cross-section, with inner and outer flanges and a connecting portion, said hoop embracing the lowermost marginal portion of said wall structure and said bottom flange and serving to hold these parts in proper relative position.

A still further object of the invention resides in providing the hoop with beads or barbs for engagement with grooves or indentations in the juxtaposed parts of the wall structure and bottom.

An object of the invention resides in forming the juxtaposed parts of the wall structure and bottom with shoulders adapted to engage one another and to hold these parts from longitudinal movement.

A feature of the invention resides in forming said beads and said shoulders by jointly scoring the parts through scoring rolls.

An object of the invention resides in constructing the wall structure with an inwardly extending rib adapted to extend into the rounded corner formed through the bending of the bottom flange from the bottom, said rib serving as a fillet for filling in said corner and for restraining longitudinal movement of the bottom with respect to the wall structure.

Another object of the invention resides in the particular construction of the hoop.

A feature of the invention resides in the method of forming the hoop in which the hoop is constructed from a strip of sheet metal bent to provide spaced parallel flanges and thereafter run through crimping rolls to shorten one of the flanges to give a circular form to the hoop.

Another object of the invention resides in the method of assembling the parts of the invention in which the hoop and adjoining parts of the container proper are simultaneously scored or otherwise mutilated to form interlocking parts for holding the bottom in position with respect to the wall structure and for holding the hoop attached to the container.

Other objects of the invention reside in the novel combination and arrangement of parts and in the details of construction hereinafter illustrated and/or described.

In the drawing:

Fig. 1 is a perspective view of a container illustrating the application of my invention thereto.

Fig. 2 is a fragmentary sectional view of the bottom construction of the container taken on line 2—2 of Fig. 1 and drawn to a larger scale. 5

Fig. 3 is a view similar to Fig. 2 showing the wall structure and the bottom of the container assembled prior to the application of the hoop thereto.

Fig. 4 is a view similar to Fig. 2 of the hoop used with the invention showing the same prior to the application thereof to the structure shown in Fig. 3. 10

In the construction of containers from sheets of paper and particularly for use as butter tubs and for similar purposes, considerable difficulty has been encountered in attaching the bottom to the wall structure of the container. Where these parts have been glued or otherwise secured together the lower rim of the container has usually 15

consisted of paper and considerable wear occurs at such locality which causes the container to lose its usefulness. At the same time where the container is used as a butter tub, it is desirable to slide the container upon concrete floors which is 20 practically impossible where the lower rim of the container is constructed of paper. The present invention provides an extremely simple and practical construction by means of which the disadvantages occurring with a paper rim are entirely 25 overcome, and by means of which the bottom may be securely attached to the wall structure of the container. 30

A container embodying my invention proper is 35 shown in Fig. 1 and comprises a body 10 open at the top which is constructed with a separate wall structure 11 and a bottom 12. The bottom 12 is attached to the wall structure 11 through a hoop 13. These various parts will now be described in 40 detail.

The wall structure 11 is preferably constructed of sheets of paper laid one upon the other and glued together to form a composite structure substantially homogeneous. The wall structure 11 when the container is used as a butter tub is 45 preferably conical as shown in Fig. 1 and is open at the top and bottom, being continuous circumferentially. The top of the tub may be closed by means of any suitable cover. Such construction forming no particular feature of the invention has 50 not been shown in the drawing.

The bottom 12 is similarly constructed from sheets of paper disposed one upon the other and glued together. The assembled sheets are pressed in suitable dies to form the bottom proper 14. 55 and a flange 15 extending downwardly therefrom. In the application of the bottom to the wall structure of the container the bottom 12 is inserted into the interior of the container. The flange 15 of said bottom is of such dimensions 60

as to cause the same to fit tightly within the lowermost marginal portion 17 of the wall structure 11 when the lower edge 18 of said flange is substantially flush with the lower edge 19 of 5 the wall structure 11. Due to the fact that the flange 15 is constructed by bending the material of the bottom, a rounded corner 16 is formed between the bottom proper 14 and the flange 15. This leaves an annular crevice 20 which 10 extends about said bottom and which is disposed between the corner 16 and the wall structure 11, as best shown in Fig. 3.

The hoop 13 is constructed from a straight narrow strip of sheet metal which is folded longitudinally along the center thereof to form a straight U-shaped structure having two spaced flanges 21 and 22 connected together through a rounded connecting portion 23 which when the hoop is applied to the container, serves as a rim on 20 which the container rests. The straight U-shaped structure so formed is then run through crimping rolls which engage the flange 22 and crimp the same to form corrugations 24 in said flange. By means of this method of construction the 25 length of the flange 22 is reduced as compared to the length of the flange 21 and the formerly straight structure converted into a curved hoop. Thereafter the ends of the flanges are secured together as by riveting, soldering or welding to 30 form a hoop of desired dimensions. A portion of a hoop so formed is illustrated in Fig. 4.

In applying the hoop 13 to the container the lowermost marginal portion 17 of wall structure 11 and the flange 15 of bottom 12 are inserted 35 into the space 25 formed between the two flanges 21 and 22 of said hoop. The lower edges 19 and 18 of these parts of the container substantially rest upon the connecting portion 23 of the hoop. While the parts are so disposed, scoring rolls 40 are applied to the outer flange 21 and a punching roll applied to the inner flange 22. These rolls are brought toward one another and as the bottom structure of the container passes between said rolls the outer flange 21 of hoop 13 is 45 formed with two inwardly extending beads 26 and 27 and the inner flange 22 is formed with a plurality of barbs 28 which extend toward the beads 25 and 27. At the same time the marginal portion 17 of wall structure 11 is formed with 50 grooves 31 and 32 which receive the beads 26 and 27 while the bottom flange 15 is formed with indentations 29 which receive the barbs 28. By means of this construction shoulders 34, 35, 36 and 37 are formed in the bottom flange 15, and 55 other shoulders 38, 39, 40 and 41 formed in the marginal portion 17 of the wall structure 11, which engage the first-named shoulders. These shoulders serve to restrain relative longitudinal movement of the flange 15 with respect to 60 the wall structure 11 of the container. Due to the fact that the material from which the wall structure 11 is constructed is somewhat flexible, a rib 33 is formed on said wall structure opposite bead 26 which extends into the interior 65 of the container. The bead 26 is so disposed that the rib 33 fills in the space 20 formed by the rounded corner 16 of the bottom 12 which serves as a fillet and at the same time provides another shoulder 30 which restrains upward movement 70 of the bottom 12 with respect to the wall structure 11. It will be noted that the hoop 13 in addition to holding the parts attached to one another and restraining relative movement thereof forms a guard which protects the lowermost 75 edges 18 and 19 of the flange 15 and the lower-

most marginal portion 17 of the wall structure 11. The rim 23 of the hoop 13 serves as a support for the container proper and also functions as a skid by means of which the container may be readily slid upon the surface on which it rests. 5

With a container constructed in accordance with my invention the bottom is firmly and securely held attached to the wall structure. Due to the rib formed on the wall structure the crevice ordinarily existing at the rounded corner between the wall structure, bottom and bottom flange is practically filled up so as to make the container more sanitary. This construction in addition assists in preventing pulling out of the bottom. By the particular method used in constructing the hoop a relatively small amount of stretching of the metal is necessary so that an extremely strong and substantial construction is provided. At the same time tinned iron or any other coated metal may be used without danger 20 if injuring the coating thereof. By means of the interlocking shoulders formed on the parts of the bottom and wall structure of the container, these parts are further held from movement relative to one another. My improved hoop construction 25 serves as a hand grip by means of which the container may be readily manipulated in the handling of the same. Our invention is extremely neat and attractive in appearance and is rigid and substantial in construction. 30

Changes in the specific form of my invention, as herein disclosed, may be made within the scope of what is claimed without departing from the spirit of my invention.

Having described my invention, what I claim 35 as new and desire to protect by Letters Patent is:

I claim:

1. In a container having a separate wall structure, a bottom extending across said wall structure, a flange extending downwardly from said bottom and along the lowermost marginal portion of said wall structure, a hoop U-shaped in cross-section having inner and outer spaced circular flanges embracing said bottom flange and the 45 lowermost marginal portion of said wall structure and having a rim connecting said flanges, the lowermost marginal portion of the wall structure being formed with spaced circumferentially extending grooves disposed one above the bottom 50 and one below the bottom, and beads on the outer hoop flange disposed within said grooves for assisting in holding the hoop attached to the wall structure.

2. In a container having a separate wall structure, a bottom extending across said wall structure, a flange extending downwardly from said bottom and along the lowermost marginal portion of said wall structure, a hoop having a flange encircling the lower marginal portion of said wall 60 structure, and a rim underlying the lower edges of said wall structure and bottom flange, the lowermost marginal portion of said wall structure being formed with spaced circumferentially extending grooves, disposed one above the bottom and one 65 below the bottom, and beads on the hoop flange, disposed within said grooves for assisting in holding the hoop attached to the wall structure.

3. In a container having a separate wall structure, a bottom extending across said wall structure, a flange extending downwardly from said bottom and along the lowermost marginal portion of said wall structure, a hoop U-shaped in cross-section having inner and outer flanges embracing the lower marginal portion of said wall structure 75

and the bottom flange and a rim underlying the lower edges of said wall structure and bottom flange, the lowermost marginal portion of said wall structure being formed with spaced circumferentially extending grooves, disposed one above the bottom and one below the bottom, beads on the outer hoop flange disposed within said grooves for assisting in holding the hoop attached to the wall structure, and means on the inner hoop flange 0 entering said bottom flange and arranged in the form of a circle intermediate the beads on said outer hoop flange for assisting in holding the hoop attached to said bottom flange.

4. In a container having a separate wall structure, a bottom extending across said wall structure, a flange extending downwardly from said bottom and along the lowermost marginal portion of said wall structure, a hoop U-shaped in cross-section, having inner and outer spaced circular flanges embracing said bottom flange and the lowermost marginal portion of said wall structure, and having a rim connecting said flanges, the lowermost marginal portion of the wall structure being formed with spaced circumferentially extending grooves disposed one above the bottom and one below the bottom, beads on the outer hoop flange disposed within said grooves for holding the hoop attached to the wall structure, and barbs on said other hoop flange extending toward said 10 beads and engaging said bottom flange, said barbs being arranged in a circle intermediate said beads.

5. In a container having a separate wall structure, a bottom extending across said wall structure, a flange extending downwardly from said bottom and along the lowermost marginal portion of said wall structure, a hoop U-shaped in cross-section having inner and outer spaced circular flanges embracing said bottom flange and the lowermost marginal portion of said wall structure 10 and having a rim connecting said flanges, the lower marginal portion of said wall structure being formed with two spaced shoulders, one of said shoulders engaging the bottom and the other being disposed immediately below the bottom, a shoulder formed on said bottom flange, and engaging the other of said shoulders, said hoop holding said shoulders in engagement with one another.

6. In a container having a separate wall structure, a bottom extending across said wall structure, a flange extending downwardly from said bottom and along the lowermost marginal portion of said wall structure, a hoop U-shaped in cross-section having inner and outer spaced circular flanges embracing said bottom flange and the lowermost marginal portion of said wall structure and having a rim connecting said flanges, spaced circumferential grooves formed upon the exterior of the lower marginal portion of the 20 wall structure, beads on said outer hoop flange fitting into said grooves, and a series of spaced barbs on said inner hoop flange entering into the bottom flange, said barbs being disposed at an elevation between the elevations of said 25 grooves.

7. In a container having a separate wall structure, a bottom extending across said wall structure, a flange extending downwardly from said bottom and along the lowermost marginal portion of said wall structure, a hoop U-shaped in

cross-section having inner and outer spaced circular flanges embracing said bottom flange and the lowermost marginal portion of said wall structure and having a rim connecting said flanges, spaced circumferential grooves formed 5 upon the exterior of the lower marginal portion of the wall structure, beads on said outer hoop flange fitting into said grooves, and a series of spaced barbs on said inner hoop flange entering 10 into the bottom flange, said barbs being disposed at the upper edge of said inner hoop flange and between said grooves.

8. In a container having a separate wall structure, a bottom extending across said wall structure, a flange extending downwardly from said bottom and along the lowermost marginal portion of said wall structure, a hoop U-shaped in cross-section having inner and outer spaced circular flanges embracing said bottom flange and the lowermost marginal portion of said wall structure and having a rim connecting said flanges, spaced circumferential grooves formed upon the exterior of the lower marginal portion of the wall structure, one of said grooves being below the bottom, beads on said outer hoop flange extending 15 into said grooves, and a series of spaced barbs on said inner hoop flange entering into said bottom flange, said barbs being disposed at an elevation between the elevations of said grooves.

9. In a container having a separate wall structure, a bottom extending across said wall structure, a flange extending downwardly from said bottom and along the lowermost marginal portion of said wall structure, a hoop U-shaped in cross-section having inner and outer spaced circular flanges embracing said bottom flange and the lowermost marginal portion of said wall structure and having a rim connecting said flanges, spaced circumferential grooves formed upon the exterior of the lower marginal portion of the 20 wall structure, one of said grooves being below the bottom, beads on said outer hoop flange extending into said grooves, and a series of spaced barbs on said inner hoop flange entering into said bottom flange, said barbs being disposed at the 25 upper edge of said inner hoop flange and below said upper groove.

10. In a container having a separate wall structure, a bottom extending across said wall structure, a flange extending downwardly from said bottom and along the lowermost marginal portion of said wall structure, a hoop U-shaped in cross-section having inner and outer flanges embracing the lower marginal portion of said wall structure and the bottom flange, and a rim underlying the lower edges of said wall structure and bottom flange, the lowermost marginal portion of said wall structure being formed with spaced circumferentially extending grooves in the exterior surface thereof and an indentation in the interior surface thereof between said first-named grooves, a projection on said bottom flange received within said indentation, and means on the flanges of said hoop for engaging said wall structure at said first-named grooves, and said bottom flange opposite said projection thereon for holding the bottom flange attached to said wall structure and said hoop attached to the container.
